WORK REST AND WHEEL MOUNT

William B. Boice, Toledo, Ohio, assignor to Boice-Crane Company, Toledo, Ohio, a corporation of Ohio

Original application August 10, 1948, Serial No. 43,393. Divided and this application December 11, 1950, Serial No. 200,243

3 Claims. (Cl. 51—239)

1

This invention relates to work holders, especially as adjustable to variable diameter rotatable work treating tools.

This invention has utility when incorporated with a grinder, wherein there is a drive for the abrasive element or wheel, and diameter reduction from wear in which the element and the holder for the work have adjustment for adaptation to the range of conditions thereby developed in practice.

Referring to the drawings:

Fig. 1 is a side elevation of an embodiment of the invention in association with a bench type of wet grinder tool, parts being broken away;

Fig. 2 is an end elevation, from the right of Fig. 1, with some portions removed;

Fig. 3 is a partial plan view of the unit of Fig. 1;

Fig. 4 is a side elevation of the direct or work supporting element, being the tertiary or third section of the assembly in Fig. 1;

Fig. 5 is a plan view, on a smaller scale of the third section of Fig. 4;

Fig. 6 is a side view of the intermediate, secondary or second section of the work rest assembly of Fig. 1;

Fig. 7 is a plan view, on the scale of Fig. 5, of the assembled third and second sections, with a broken away portion to show the mounting at one side with the primary section; and

Fig. 8 is a fragmentary side elevation of the base, primary or first section of the work rest assembly of Fig. 1.

Upon a bench or support 1, screws 2 may anchor sheet metal feet or brackets 3 as weld-assembled with a receptacle or vessel 4, adapted to retain a cutting-promoting substance or water 5. Set screws 6 provide for mounting a removable lid or cover 7 forming an extension means or housing portion on the top of the vessel or support 4 therefor.

A base 8 on the bench 1 provides a support for a prime mover or electric motor 9 having, on its shaft 10, a pulley 11 for a V-type belt 12 to a driven pulley 13, fixed by a set screw 14 with a shaft 15. The shaft 15 has bearings 16 in a U-bracket 17 swingable on a bearing pin 18 mounted by parallel cheek portions or flanges 19 rising from the lid 7 about an opening 20. A cover 21, spanning between the pin 18 and the shaft 15, forms a partial shield 22 over a friction drive rubber-faced roller 23. The roller 23 is yieldably held to peripherally engage an abrasive disk or grinding element 24 upwardly protruding from the opening 20 between the flanges 19.

2

A torsion spring 25, having its ends 26 engage the flanges 19 and with spring wraps about the pin 18, has a medial loop 27 engaging the underside of the cover 21, thereby urging the roller 23 against the grinder or work treating tool 24.

The grinder wheel 24 is rotatably mounted with the wheel having its bearing on a shaft 28. The shaft 28 has flattened end portions 29 having centrally thereto internally threaded seats 10 adapted to be engaged by externally threaded cap screws 30 thru slots 31 in the lid 7 adjacent the flanges 19. The slots 31 are parallel in a plane lateral to a horizontal radius from the shaft 15. The shaft or bearing 28 for the wheel 24 is thus adjustable relatively to the support 4 and along the lid 7. Adjusted proximity for efficient contact between the driving friction roller 23 and the driven disk 24 is determined and caps 32 on the stems 30 clamp lock the disk 24 against shifting therefrom during operation.

Inasmuch as the disk 24 is of approximately uniform abrasive body throughout and the use gradually wears off small particles to reduce effective or working diameter, the resetting permitted 25 thru the slots 31 may be undertaken in compensation for wearing down the wheel 24. Inasmuch as the drive roller 23 has peripheral contact, this means that, even tho the diameter of the work-engaged wheel 24 may be reduced, its 30 linear peripheral speed will be maintained. Notches 33 in the flanges 19 provide clearance for the shaft 15 to swing downward in maintaining its frictional driving contact with the disk 24.

35 Remote from the notches 33, the flanges 19 have a higher shield or housing portion 34 astride, or embracing the wheel 24. The portion 34 has therein a pair of slots 35, transversely in register, which slots 35 extend toward the frame lid 40 or cover 7 and the bearing for the wheel 24 on the shaft 28. The lot 35 are parallel to a top edge region or portion 36 extending to the flange portions 19. There is thus provided the primary work rest section in the form of an adjustment 45 seat portion or base.

A pair of angle plates have downwardly extending wings 37 from outwardly extending plate portion 38. The portions 38 are adapted to ride on the edge portions 36 with the wings 37 overlapping a portion of the inner face of the slots 35. The upper portions of the portions 38 away from the edge portions 36 provide a pivot bearing 39 alignment feature of this secondary work rest section.

55 A pair of arc flanges 40 extend downward

away from top connecting or cross portion 41. This tertiary section of the work rest is hinge mounted on the bearing 39. The arc flanges or wings 40 ride on the side of the slots 35 opposite from the overlap 37. The flanges 40 have arc clearance 42 from the pivot bearing 39. Offsets or lugs 37' from the plate 37 ride in the slots 35 and hold the intermediate or secondary section plate 37 from tilting. Radially outward from the clearance 42, there are arc slots 43 in the wings 40.

A head 44, on a pin 45 as a threaded extension or bolt, is toward the wheel 24 from the wings 37. From the head 44, the threaded portion 45 of the bolt extends thru an opening in the wing 37 and the slot 35, as well as on thru the slot 43. A nut 47 may shift a washer 47'' to position astride the slot 35 and in such clamp assembly hold the secondary section at an adjusted position with the primary section, leaving the threaded extension 45 protruding outward thru and clear of the slot 43. A clamp washer 46 of central clearance as to the nut 47' and the washer 47'', may be thrust along over the bolt portion 45 to contact the wing 40 having the slot 43. A wing nut 47 on the threaded portion 45 is now adjusted to force the washer 46 firmly against the wing 40. There is thus effected a holding of the tertiary work rest section at adjusted angle as to the wheel 24 and so fixed thru the intermediate and primary work rest sections.

It is thus seen that thru loosening of the wing nuts 47, as aligned transversely of the wheel, or parallel to the shaft 28, there may be a rocking of the tertiary work rest 40, 41, to take a desired angle relatively to the working face of the wheel 24, for the convenience of the operator in efficiently directing the work to be engaged by the wheel 24. While the bolts 44, 45, are common for this rocking adjustment, and for the radial slide adjustment, which latter is between the primary and secondary sections, this latter setting or adjustment is not disturbed in the relocation of the tertiary work rest 40, 41. However, in order to adjust the radial range of the secondary and tertiary sections relatively to the wheel 24, there is the release of the tertiary section from the secondary section to expose the nuts 47' to access for loosening and the shifting of the secondary section along the slots 35, with a retightening of the nuts 47'. In the sequence of operations, it is now in order to complete the work rest assembly of its multi-sections by setting the wing nuts 47 to fix the tertiary section with the now reset primary and secondary sections.

An arrow 48 indicates the direction of rotation of the abrasive element 24, herein shown as clockwise (Fig. 1). This means that the friction driving roller 23 has a counterclockwise direction of rotation. The firm driving relation of the roller 23 on the periphery of the element 24 seems to reduce the liquid to a film condition of spreading and minimizes the tendency to have any liquid thrown therefrom toward the operator. A down direction reach is indicated by an arrow 49 for the belt 12, which in conjunction with the spring 25 establishes a practical holding-in or driving relation for the roller 23 with the element 24.

This case is a division of Serial No. 43,393, filed August 10, 1948, which has developed into U. S. Patent No. 2,537,394 January 9, 1951.

What is claimed and it is desired to secure by Letters Patent is:

1. In an abrasive wheel assembly having a bearing for the wheel and a support for the bearing, a tool rest device comprising: a wheel shield means rising from the support, said means including an inclined edge and parallel thereto a slot toward the bearing, plate means adapted to seat on said edge with an angular portion therefrom extending along the inner face of the shield means across the slot, said plate 10 locating a bearing parallel to the wheel bearing axis, a work rest mounted in the plate-means-provided bearing, said rest having flanges depending against the outer face of the shield means and having an arc slot aligned with the 15 plate means bearing, and a clamp pin through the plate means angular portion, the shield means inclined slot and the flange arc slot, adapted to set the work rest at different angles relative to the plate means and at different positions along the inclined slot.
2. In a work treating wheel assembly having a bearing for the wheel and a support for the bearing, and means for adjusting said bearing relative to said support, a tool rest device comprising: a housing portion fixed to said support and extending about a portion of said wheel said portion having an edge region parallel to a radius of said wheel from said bearing, slot means parallel to said edge region in forming one work rest 30 section, another work rest section overlapping said slot means, and bolt connection means at said overlap and slot means providing adjustment of said another work rest section along said edge region toward the wheel to the location of the wheel from adjustment of the bearing relatively to the support.
3. In an abrasive wheel assembly having a rest adjacent the grinding surface of said wheel for articles to be abraded, said rest comprising: a shield adjacent the side of said wheel and having a longitudinal slot extending substantially inwardly from said grinding surface permitting adjustment to compensate for wear of the abrading surface of said wheel, a hinge bracket, a bolt 45 and nut extending through said slot and hinge bracket for adjustably clamping said hinge bracket in a preselected position along said slot, a tiltable table article support portion pivotally hinged on said bracket, said table having a flange 50 with a slot arcuate to the axis of said hinge and straddling said bolt and nut, and clamp washer and second nut means on said bolt for adjustably clamping said table in a preselected angular position about said hinge axis.

60 WILLIAM B. BOICE.
